AZEL C. HOUGH, OF JANESVILLE, WISCONSIN, ASSIGNOR TO HOUGH SHADE CORPORATION, OF JANESVILLE, WISCONSIN, A CORPORATION OF CONNECTICUT.

SHADE-FIXTURE.

1,187,458.

Specification of Letters Patent. Patented June 13, 1916.

Application filed September 17, 1914. Serial No. 862,183.

To all whom it may concern:

Be it known that I, AZEL C. HOUGH, a citizen of the United States of America, residing at Janesville, in the county of Rock 5 and State of Wisconsin, have invented a new and useful Shade-Fixture, of which the following is a specification.

My invention relates to cord-supporting devices designed to be attached to flexible 10 shades of the type that are capable of being rolled up and unrolled through the medium of cords, and consists of a member that is adapted to be hooked over the top molding of a shade, and is "broken out" to form a 15 pointed tongue with which to secure one end of the roll-up cord and also to fasten said member to said molding, said member having an opening therein for a supporting screw, and being provided with a suitable 20 lug for said cord to run in or slide through, all as hereinafter set forth.

The objects of my invention are, first, to produce a comparatively simple and inexpensive, yet strong and durable fixture, for 25 so-called porch shades and the like, that can be readily attached to a shade and have as readily attached thereto the upper end of the roll-up cord for such shade, both attachments being secure and permanent, and, sec- 30 ond, to provide means in connection with such fixture to fasten both the fixture and the shade molding upon which it is mounted to the part of the porch or building that supports the shade, whereby practically all 35 of the strain which comes on the fixture and the shade from the cord, and would other- wise be sustained by said fixture and shade, is transferred directly to the aforesaid sup- porting part of porch or building.

40 Other objects will appear in the course of the following description.

I attain the objects and secure the advantages of my invention by the means illustrated in the accompanying drawings, in 45 which—

Figure 1 is a front elevation of the central portion of the top and bottom parts of a porch shade, and of a preferred form of my fixture attached to the upper molding 50 of such shade, the head of the supporting screw being shown in dotted lines; Fig. 2, a rear elevation of the same elements, except that the aforesaid screw is not shown; Fig. 3, an edge view of said fixture before the

tongue is bent over to engage the cord and 55 penetrate the upper molding, the latter being represented in cross-section, and said supporting screw appearing in full lines; Fig. 4, a top plan of said fixture and a fragment of said molding, the tongue here 60 being bent into operative and engaging position, but the cord being omitted; Fig. 5, a rear elevation of a slightly modified form of fixture, showing the tongue before it is bent over the cord and driven into the molding, 65 and, Fig. 6, a front elevation of still another modified form of fixture, the tongue being unbent in this case also. No molding is shown in either of the last two views.

Similar reference numerals designate 70 similar parts throughout the several views.

Those portions of the shade appearing in connection herewith comprise top and bottom moldings 10 and 11, respectively, intermediate slats 12, and warp strands 13, each 75 of such moldings consisting of two pieces, as shown in Figs. 3 and 4, between which the corresponding terminals of said warp strands are received. A roll-up cord 14 is provided for the shade, such cord being long 80 enough to extend from the top of the shade at the back, down under the bottom of the shade, when the latter is extended full length, up to the top in front, and then down again as far as may be desired. The 85 construction and operation of these elements are old and well known, and require no extended explanation; furthermore, the details of construction may vary in different makes 90 of shades.

Passing now to the fixture, it will be observed that the same comprises a front part or what may be termed a body 15, which is provided at the bottom with a hook or lug 16 for the cord 14 to run in or through, and 95 which has an opening 17 therethrough, a hooked part that extends rearwardly from the top of said body, as shown at 18, and then extends downwardly to form a lip 19, and a tongue 20. The aforesaid hooked rear part of the fixture is so proportioned that it fits over the molding 10, the body 15 being in front, the lip 19 behind, and the top 18 on top of said molding. The opening 17 is provided to receive a screw 21, which also 100 passes through an opening 22 in the molding 10 behind said opening 17.

The tongue is preferably struck out of the

lip 19, as shown in the first four views, but may be struck out of the top 18, as shown in Fig. 5, or out of the front or body 15, as shown in Fig. 6. A slot 23 is left in the 5 part out of which the tongue 20 is formed, and said tongue is capable of being turned or bent over to reenter with its free end such slot. The tongue should be formed with its free end sharp or pointed, substantially as shown at 24, so as to enable the 10 same, after reentering its slot 23, to be driven into the molding 10. The length of the tongue is sufficient to permit the latter to be bent over the cord 14 and driven the 15 required distance into the molding 10.

It will be seen that this fixture can be formed out of a single piece of sheet-metal, with the aid of suitable punches and dies.

In practice, the fixture of the first four 20 views is placed in proper position on the molding 10, and then the cord 14 near one end is laid in the angle, which the tongue 20 initially makes with the lip 19, and said tongue is bent over said cord, its pointed 25 end 24 passing in the slot 23, and driven into said molding. When the bent tongue 20 is driven into the molding 10, said tongue firmly grips the cord 14, below a knot 25 that should be tied therein at what is now 30 the upper end thereof, and securely holds said cord or said end against any reasonable downward pull thereon, the cord being tightly confined between the contiguous edges of the slot 23 and said tongue; and, 35 at the same time, said tongue, by reason of its engagement from the rear with said molding, secures the fixture thereto so that it can not be lifted off the same or otherwise become displaced or detached. Next, 40 the molding 10 with the fixture is suspended in the usual manner and by the usual means, and the screw 21 is inserted in the openings 17 and 22 and screwed into the shade support, that is, into the part of the porch or 45 building to which the shade is attached.

The cord 14, after having one end secured 50 to the fixture, as explained, and which hangs down behind the shade, is brought forward under the shade, carried up in front of the same, passes through the lug 16, and left with the other end loosely pendant, as shown. The shade is rolled up by grasping the loosely pendant end of the cord 14 and drawing down on the same to shorten the 55 loop beneath the shade, and said shade is unrolled by slackening the grasp on the free terminal portion of said cord and permitting said loop to lengthen. During either of these operations the weight carried by 60 and the strain on the cord 14 comes directly on the fixture and the molding 10, as will be readily seen, but such weight and strain are in great measure, through the medium of the screw 21, transferred to the porch or 65 building supporting member. This enables

me to use a lighter fixture, and relieves the same together with the upper part of the shade itself from much strain that might and frequently would be detrimental.

If the tongue 20 be struck out of the top 70 18, as is the case with the fixture shown in Fig. 5, said tongue, when bent over to grasp the cord and enter into engagement with the molding, will securely hold the former, but cannot make as good an engagement with 75 the latter as when said tongue is struck out of the lip 19, or out of the body 15 as in the last view. In other words, the tongue in the Fig. 5 construction enters the molding from above, instead of from one side or the other, 80 and consequently would be liable to pull out in the event force which had a tendency to separate the fixture from the molding, or vice versa, were applied, but said tongue holds said fixture against endwise displacement. To supplement this tongue and hold the fixture down on the molding, nails or screws (not shown) may be inserted in holes 85 26 in the lip 18 and driven into the molding, or some other equally well-known extra 90 fastening or securing means may be employed.

In the Fig. 6 construction the tongue 20 is struck out of the body 15, but said tongue is the same in all other respects and functions in the same way as when struck out of the lip 19. In this construction the knot 25 is located below the tongue, when the latter is bent over the cord 14, and said cord passes up, over, and down behind the 95 fixture; and in the Fig. 5 construction said knot is in front of the bent tongue, and passes backwardly and then downwardly.

While it is true that the screw 21 fastens 100 the fixture securely to the molding, said screw is not used until the shade is actually 105 installed, hence means such as the tongue is needed to secure the fixture from the time it is applied to the shade by the manufacturer until said shade reaches the hands of the consumer and by him is hung up for 110 practical purposes.

Various modifications in shape, size, construction and arrangement of the parts and members of this device, such as will occur 115 to one skilled in the art, and in addition to those hereinbefore specifically mentioned, may be made without departing from the spirit of my invention. In this connection, it should be noted that, although the supporting screw 21 is believed to be the best medium for the purpose, I 120 might use some other medium, such as a nail for example.

What I claim as my invention, and desire to secure by Letters Patent, is—

1. As an improved article of manufacture, a shade fixture comprising a hook portion adapted to support the fixture from the top of a shade, a tongue formed from 130

said hook portion and adapted to be bent into engagement with a cord to hold the same, and at the same time to be driven into engagement with said shade to secure the 5 fixture thereto, and a depending part adapted to support said cord and permit the latter to slide.

2. As an improved article of manufacture, a shade fixture comprising a hook portion adapted to support the fixture from the top of a shade, a tongue formed from said hook portion and adapted to be bent into engagement with a cord to hold the same, and at the same time to be driven 10 into engagement with said shade to secure said fixture in place, and a depending part for the running portion of said cord, said depending part having an opening therein 15 to receive a member, as a screw, wherewith the strain on the fixture and shade, from 20 said cord, is transformed from the fixture

and shade to the part of the building to which the shade is attached.

3. The combination, with a shade having a perforated top member, and a roll-up 25 cord, with a fixture comprising a supporting part to engage said top member, a part to engage and hold said cord, and a depending part for the running portion of said cord, said depending part being perforated 30 to correspond with the perforation in said top member, and a supporting member adapted to pass through the perforations, in said depending part and said top member, into a fixed support, whereby the strain 35 on the fixture and shade, from said cord, is transferred from the fixture and shade to the fixed support.
